US00D733497S

(12) **United States Design Patent**
Sorensen et al.

(10) **Patent No.:** **US D733,497 S**
(45) **Date of Patent:** ** *Jul. 7, 2015

(54) **CONTAINER**

(71) Applicant: **Runway Blue, LLC**, Pleasant Grove, UT (US)

(72) Inventors: **Steven M. Sorensen**, Alpine, UT (US); **David O. Meyers**, Kaysville, UT (US); **Kim L. Sorensen**, Alpine, UT (US)

(73) Assignee: **RUNWAY BLUE, LLC**, Pleasant Grove, UT (US)

(*) Notice: This patent is subject to a terminal disclaimer.

(**) Term: **14 Years**

(21) Appl. No.: **29/465,998**

(22) Filed: **Sep. 3, 2013**

(51) LOC (10) Cl. **07-01**

(52) U.S. Cl.

USPC **D7/509**

(58) **Field of Classification Search**

(57) **CLAIM**

The ornamental design for a container, as shown and described.

DESCRIPTION

FIG. 1 is a upper perspective view of an embodiment of a container;

FIG. 2 is a lower perspective view of the container shown in FIG. 1;

FIG. 3 is a front view of the container shown in FIG. 1;

FIG. 4 is a rear view of the container shown in FIG. 1;

FIG. 5 is a left side view of the container shown in FIG. 1;

FIG. 6 is a right side view of the container shown in FIG. 1;

FIG. 7 is a top view of the container shown in FIG. 1;

FIG. 8 is a bottom view of the container shown in FIG. 1;

FIG. 9 is an upper perspective view of another embodiment of a container;

FIG. 10 is a lower perspective view of the container shown in FIG. 9;

FIG. 11 is a front view of the container shown in FIG. 9;

FIG. 12 is a rear view of the container shown in FIG. 9;

FIG. 13 is a left side view of the container shown in FIG. 9;

FIG. 14 is a right side view of the container shown in FIG. 9;

FIG. 15 is a top view of the container shown in FIG. 9; and,

FIG. 16 is a bottom view of the container shown in FIG. 9.

The broken lines shown in the figures depict unclaimed portions of the container only and form no part of the claimed design.

1 Claim, 16 Drawing Sheets
